(57) CLAIM

The ornamental design for a UV fingernail curing lamp, as shown and described.

DESCRIPTION

FIG. 1 is a perspective view of a UV fingernail curing lamp showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view from the back side.

The broken lines along the opening of the lamp in FIGS. 3, 7 and 8 illustrate the bounds of the claim. The remaining broken lines illustrate portions of the lamp. None of the broken lines forms no part of the claimed design.
